UNITED STATES PATENT OFFICE.

NIKOLAUS SCHRÖDER, OF CLEVELAND, OHIO.

GAS-STOVE.

1,183,042.

Specification of Letters Patent.

Patented May 16, 1916.

Application filed February 12, 1916. Serial No. 77,950.

To all whom it may concern:

Be it known that I, NIKOLAUS SCHRÖDER, a subject of Hungary, residing at Cleveland, in the county of Cuyahoga and State of Ohio, have invented certain new and useful Improvements in Gas-Stoves, of which the following is a specification.

This invention relates to gas stoves, and is an improvement comprising the construction and arrangement of parts substantially as hereinafter shown and described and more particularly pointed out in the claims.

The object of the invention is to provide a practical and efficient gas stove of attractive and ornamental form which may be used safely in a room to heat the air therein without exposing the occupants to any danger or annoyance from the gas or fumes.

A further object is to obtain a large area of radiation and a free and uninterrupted flow of air through the stove.

A further object is to provide means for furnishing fresh air to the burner of the stove from a source outside of the room or 25 the building in which the stove is located.

In the accompanying drawings, Figure 1 is a perspective view of my improved gas stove. Fig. 2 is a vertical section, front to rear, of the stove. Figs. 3 and 4 are sectional detail views of the protecting device for the burner air supply pipe, these views being taken on line 3-3 and 4-4, of Figs. 4 and 3, respectively. Fig. 5 is a front view and section looking inward from line 5-5, Fig. 2, a portion of one air flue being also broken away to disclose its interior formation. Fig. 6 is a cross section in plan on line 6-6, Fig. 2. Fig. 7 is a cross section in plan of the burner chamber on line 7-7, Fig. 5. Fig. 8 is an enlarged detail view of the gas supply pipe and the valves connected therewith. Fig. 9 is a side view of the guard or shield which is used in connection with the pilot valve.

The structural features of the stove are distinguished in that the main sheet metal body is secured upon and carried by a cast metal border frame 2 mounted upon a base 3 having corner legs, said frame and body being curved at its front lower portion and extended upwardly and at an inclination at its upper front-portion. An air heating chamber 4 is provided within the rear part of the stove. The lower front curved part 55 of the stove contains a burner chamber 5, access to which may be had through a

hinged door 6. A gas burner 7 for the stove is seated within the bottom of chamber 5 and comprises an air distributing and mixer pipe 8, and two perforated burner pipes 9 arranged parallel with and on opposite sides of pipe 8. These pipes are connected with a T-shaped distributing head 10, and the gas is supplied to pipe 8 through an angular nipple 11 having a valved connection 12 with the gas supply pipe 13 mounted outside of the stove. The air is supplied through a vertical branch pipe 14 connected with the bottom of nipple 11 and having a regulating valve or damper 15 therein. A lateral extension 16 of pipe 14 supplies fresh air from a source outside of the room or building containing the stove, and the outer end of this extension is provided with a semi-spherical hood 17 and a gauze closure 18 to guard and protect the intake end of said air supply pipe from draft and dust. The air distributing tube 8 is divided longitudinally by a wall 19 therein and a series of fresh air outlet orifices 20 are provided on each side of said tube beneath said division wall opposite the gas burner pipes 9. The gas supply connection 12 is directly opposite the open end of the upper chamber within pipe 8, and the air which is supplied from pipe 14 is mixed with the gas and the mixture carried forward to the burner pipes through said upper chamber. On the other hand, a portion of the air supplied to pipe 14 is also free to pass into the lower divisional space within pipe 8 and out of the orifices 20 so as to supply the burner chamber 5 with a supply of fresh air and promote combustion at the burner pipes 9, and the air and mixture is also preheated by the arrangement and relationship of pipes as described.

The products of combustion and the heat not otherwise radiated through the walls of chamber 5 pass upwardly through a series of rectangular flue boxes or tubes 21 arranged in stepped relationship at the rear and top of the stove between the extended sides of the border frame 2. Each flue box has a central communicating passage 22 at its front and bottom, the first or lower flue box 21 communicating in this way with chamber 5, and the next higher or middle box having its passage 22 opening into the rear of the first mentioned box, whereas the last or upper box 21 in the tier is open at 110 22 to the middle box 21. The final discharge from the stove is through a short neck 23

at the rear of the upper box 21, and any suitable pipe connection may be made therewith, and if preferred this connection may be hidden by an ornamental crown member 24 5 forming part of the border frame 2. Each flue box 21 has a walled passage 25 extending therethrough from top to bottom through which the air from chamber 4 is permitted to rise and escape. The walled passage 25 is relatively long and narrow in width and divides the flue box longitudinally so as to cause the products of combustion to pass to opposite ends of each box before escaping into the next higher flue 15 box. The full area of each flue box is thus utilized in the most effective way to radiate the heat, and the number of flue boxes made and arranged in this way may be greatly augmented without seriously affecting the 20 natural draft necessary to carry away the fumes from the burner chamber 5.

Lighting of the gas burner may be effected at the side of the stove by first igniting a valved pilot light 26 which is affixed to gas supply 25 pipe 13 opposite a guarded entrance opening 27 in the side wall of the burner chamber 5. The guard or closure for this opening 27 comprises a plate 28, and an opening 29 at one side of the center of this plate is adapted 30 to register with opening 27 when the plate is moved to its maximum distance to the right by engaging the projecting finger 30 which extends through the segmental slot 31 within the housing 32, see Figs. 8 and 9.

35 The main walls of the stove are made of sheet metal, preferably, and all joints securely sealed, the door 6 being also mounted to maintain close sealing relations with the border frame 2 and having a suitable locking handle 34 to assure a tight fit at all points. Any suitable sealing material, such as strips 33 of asbestos, may be used to close the joints in the stove.

What I claim is:

45 1. In a gas stove, a casing having a combustion chamber at its front and an air chamber at its rear, and a series of stepped boxes in open communication with said combustion chamber and each other at the top 50 of said air chamber and having walled air passages extending vertically therethrough.

2. A gas stove body having a burner chamber at its front and a tier of flue boxes in

stepped relation at its rear in open communication centrally with said burner chamber and each other, each flue box having a walled air passage dividing the box into separate circulating passages. 55

3. A gas stove comprising a chambered body having a curved front and offset portions at its rear upper end, said offset portions having air passages vertically therethrough, in combination with a gas burner within the lower front end of said body. 60

4. A gas stove body having a burner chamber at its front and a tier of rectangular flue boxes in stepped relation at its rear and in open communication centrally with the upper end of said burner chamber and each other, each flue box having a vertical walled 70 air passage extending longitudinally within a relatively short distance of the opposite ends of the box. 75

5. A gas stove having a burner chamber and a series of stepped tubular flue boxes 80 open thereto, and a gas burner having separate gas and air connections and a divided tube for distributing a gaseous mixture and fresh air separately to said burner and chamber. 85

6. A gas stove having a burner chamber at its front and stepped flue-boxes at its rear, a gas burner within said chamber, valved gas and air connections for said burner, a pilot light outside said stove, and said chamber 90 having a guarded entrance opposite said pilot light. 95

7. A gas stove having a burner chamber and a door therefor at its front and a tier of tubular flue boxes in stepped relation in 100 open communication with the upper end of said chamber and each other, in combination with a gas burner and fresh air distributing pipe within the bottom of said chamber having a valved gas connection extending into one side of said chamber and a valved air pipe projecting downwardly through the bottom thereof, and a horizontal air intake pipe for said valved pipe having a draft protector at its end. 105

In testimony whereof I affix my signature in presence of two witnesses.

NIKOLAUS SCHRÖDER.
